UNITED STATES PATENT OFFICE.

LUTHER B. HETRICK, OF ELWOOD, INDIANA.

GINSENG-SHADE.

1,001,267.

Specification of Letters Patent. Patented Aug. 22, 1911.

Application filed March 6, 1911. Serial No. 612,548.

To all whom it may concern:

Be it known that I, LUTHER B. HETRICK, a citizen of the United States, residing at Elwood, in the county of Madison and State 5 of Indiana, have invented certain new and useful Improvements in Ginseng-Shades, of which the following is a specification.

This invention relates to structures for growing ginseng, and the object of the invention is to provide a simple, cheap and effective ginseng frame that is easy of erection, 10 economical of construction and yet embodying all the essential elements necessary to the proper cultivation of ginseng.

15 Among the essentials necessary to the successful propagation of ginseng are the proper distribution of light and shade, protection from too abundant supply of rain water and protection from the direct rays 20 of the sun in hot weather, and direct exposure to the abundant dews at night without excluding the necessary amount of air. And this must be accomplished without too 25 great an expenditure of time or material. I aim to accomplish the desired end by a series of adjustable shades mounted on posts or standards at a convenient height above the head and running parallel to one another. They can be of any length and 30 multiplied indefinitely until the required amount of ground is covered and the sides closed in by especially constructed frames as clearly illustrated in the drawings.

Other objects and advantages will develop through the progress of the specification and will be more specifically noted with reference to the accompanying drawings.

Referring to the drawings: Figure 1 illustrates in side elevation a section of my improved frame with shade down, Fig. 2 illustrates an end or side section of my frame in perspective, Fig. 3 illustrates in perspective two frames with shades extended, and Fig. 4 illustrates a front sectional elevation of a 45 number of frames with shades extended.

Like numerals of reference indicate corresponding parts throughout the specification and in the several views.

Referring to Figs. 1, 3 and 4 of the drawings, 50 1 indicates posts or standards set in center of beds 2. Dovetailed to the top of posts 1 are T-shaped members 3 to the under side of which are hinged or pivoted shades 4, said shades 4 being made of palings or laths, of any desired width, spaced substantially $\frac{1}{2}$ inch apart, and united by

strips 5 running at right angles therewith. Hooks or snaps and eyes 6 are mounted on the ends of shades 4 and are adapted to engage with one another and support said shades in an elevated position when it is desirable to have them extended for the purpose of keeping out too direct rays of the sun or as protection against too much rain in wet weather. T-shaped members 7 are 60 spaced at convenient intervals from frame to frame extending horizontally over the top thereof and rigidly secured thereto, and serve as additional supports to said frames as illustrated in Fig. 3. Only two sets of 65 frames are shown in the illustrations, still it is evident that any number of these sets may be placed side by side until any required surface is covered and they are so arranged that the shades depending therefrom 70 may be raised or lowered at convenient intervals, as for instance, when it is necessary to exclude too direct rays of the sun in hot weather or shed an excessive downpour of rain. Also in winter when it is not 75 necessary for the shades to be extended they can be lowered in order that the weight of snow will not bear too heavily upon the frame. This arrangement also permits the snow to go through when the shades are 80 lowered and cover the bed which is desirable as a protection against excessive freezing. It will be noted that the shades are hinged directly under the T-shaped member 3 in 85 such a manner that the hinges will be afforded protection from rain and consequent rust. 90

Referring to Fig. 2 of the drawings: 1 indicates standards or posts. 2 is a bed for growing ginseng into which said posts are firmly planted. 3 is a T-shaped tying member. 4 are horizontal braces rigidly secured to the middle of posts or standards 5. 6 are top and bottom members to which upright palings or laths 7 are nailed. Palings or laths 8 are nailed from the T-shaped 95 tying member 3 to top member 6 forming a roof or covering over this section of the device. The section of the device described and shown in Fig. 2 is intended to close in the four sides of the completed garden and 100 when added to the parallel frames shown in Fig. 3 forms a complete closure such as is desired for the purposes as specified. Between each series of frames, walkways or paths 8 are provided which are slightly 105 lower than the beds 2 and serve the double purpose of keeping persons off the beds and 110

also allowing the excess of water to run off between the beds in wet weather as it drips from the palings.

Having described my invention, that which I claim as new and desire to secure by Letters Patent is:

1. In combination a frame for growing ginseng comprising standards, T-shaped members connecting said posts, blinds or shades depending from said T-shaped members, said blinds or shades comprising palings or laths spaced apart from one another and hinged to said T-shaped members and means for supporting said blinds or shades in extended position, as specified.
2. In combination parallel frames for growing ginseng, said parallel frames com-

prising standards, T-shaped members connecting said standards, blinds or shades hinged to said T-shaped members, means for sustaining said blinds or shades in an extended position by locking one set of shades to its complementary adjoining set of blinds or shades in such a manner as to form a sloping roof, and means for inclosing the frames to form a completed shaded closure for the purposes specified.

In testimony whereof I affix my signature in presence of two witnesses.

LUTHER B. HETRICK.
